(57) **CLAIM**

The ornamental design for a lamp as shown and described.

DESCRIPTION

1. Lamp

1.1 : Perspective

1.2 : Front

1.3 : Back

1.4 : Left

1.5 : Right

1.6 : Bottom

1.7 : Top

The broken lines shown in the figures illustrate portions of the lamp which form no part of the claimed design; the break lines and curly brackets shown in Figures 1.1 to 1.3, 1.6, and 1.7 illustrate symbolic breaks which form no part of the claimed design; the appearance of any portion of the lamp between said break lines forms no part of the claimed design.

1 Claim, 7 Drawing Sheets
